(21) Appl. No.: **29/170,154**

(57) **CLAIM**

(22) Filed: **Nov. 2, 2002**

The ornamental design for a palm grip sander, as shown and described.

(51) LOC (7) Cl. **08-01**
(52) U.S. Cl. **D8/62**
(58) Field of Search D8/61, 62, 67, D8/69; 173/168, 169, 170, 171, 217; 310/47, 50; 451/344, 351, 355, 356, 357, 358, 359, 451, 453, 456

DESCRIPTION

(56) **References Cited**

FIG. 1 is a front perspective view of the present new design for a palm grip sander;
FIG. 2 is a left side view thereof;
FIG. 3 is a right side view thereof;
FIG. 4 is a front view thereof;
FIG. 5 is a rear view thereof;
FIG. 6 is a top view thereof; and,
FIG. 7 is a bottom view thereof.

The broken lines showing various features of a palm grip sander are for illustrative purposes only and form no part of the claimed design.
